INVENTOR
JOSEPH N. BORROUGHS

BY

Harry Schröder,
ATTORNEY

UNITED STATES PATENT OFFICE.

JOSEPH N. BORROUGHS, OF OAKLAND, CALIFORNIA.

TOWEL CABINET.

Application filed October 23, 1922. Serial No. 596,246.

To all whom it may concern:

Be it known that I, JOSEPH N. BORROUGHS, a citizen of the United States, residing at Oakland, in the county of Alameda and State of California, have invented certain new and useful Improvements in Towel Cabinets, of which the following is a specification.

My invention is an improved towel cabinet.

A considerable amount of time is wasted, and it is quite difficult, to insert a clean towel on its roller in the cabinet. The towel roller has been mounted on bearings heretofore, which increased the expense of construction and necessitated a considerable number of extra parts, such as a brake, a spring, and so forth.

The object of my invention is to provide a suspension means for the supply roller in which the roller may be quickly placed and which is simple in construction and efficient in operation.

A further object of my invention is to provide a control means to limit the amount of towel which can be withdrawn.

Other objects and advantages will appear in the course of the specification.

Referring to the drawing which forms a part of this specification:

Figure 1 is a front elevation of my towel cabinet with the door in its open position.

Figure 2 is a sectional view taken on the line 2—2 of Figure 1.

Figure 3 is a fragmentary sectional view taken on the line 3—3 of Figure 1.

Figure 4 is a face view of the releasing mechanism and control gear.

Figure 5 is a fragmentary sectional view taken on the line 5—5 of Figure 3.

Figure 6 is a plan view of the supply roller basket.

Figure 7 is a sectional view taken on line 7—7 of Figure 6.

Referring more particularly to the drawing, the numeral 1 indicates a towel cabinet comprising side walls 2 and 3, a door 4 and a lower front wall 5.

A supply roller basket 6 rests upon brackets 7 and 8 which are secured to the side walls 2 and 3. The basket 6 comprises a rim 9 from which depend a plurality of supporting straps 10. The roll of toweling is dropped into the basket 6 and rests loosely upon the straps 10. No painstaking care is

required to insert a clean towel supply in the cabinet.

A supply roller 11, covered with corrugated rubber, is journaled in the side walls 2 and 3 at the rear of the cabinet 1 and under the basket 6. A pressure roller 12 is mounted upon straps 13 which are pivoted at 14 in the side walls 2 or 3. Springs 15 are secured to the straps 13 and to the walls 2 or 3 to urge the roller 12 against the roller 11. A take-up roller 16 is journaled in the side walls 2 and 3 below the roller 11 and forwardly thereof, and a pressure roller 17 bears against it. The roller 17 is mounted on straps 18 which are pivoted at 14 and a spring 19 is secured to the strap and the wall 2 or 3 to urge the roller 17 against the roller 16. The edges of the supply roller 11 are tapered as at 11' and the edges of the take-up roller 16 are tapered as at 16' which prevents the towel from travelling over the edge of the rollers. A slot 20 is formed in the door 4 to allow for the emission of the towel. A notch 21 is formed in the lower edge of the door 4 to admit the towel into the cabinet 1.

A plate 22 is secured to the lower edge of the slot 20 and extends inwardly over the rollers 16 and 17 to prevent the clean towel from coming in contact therewith. A second plate 22^a is inserted across the cabinet under the plate 22 to prevent the moisture which rises from the damp towel below from penetrating the clean roll above. A plurality of wires 23 are loosely hung from the roller 16, the lower ends of which wires are secured to a rod 24. The wires 23 prevent the soiled towel from rewinding around the roller 16 and thus obstruct the action of the cabinet.

Secured to one end of the roller 16 adjacent the wall 2 is a gear 25, and a gear 26 is secured to the end of the roller 11. An idler gear 27 is journaled in the wall 2 and meshes with both gears 25 and 26. Meshing with the idler gear 27 is a control gear 28. A stop bar 29 is secured to the gear 28 and one end thereof projects slightly beyond the periphery of the gear and is adapted to engage a trigger 30. The trigger is pivoted to the wall 2 below the gear 28 and the upper end is arcuate in shape as at 31 to conform to the shape of the gear. A lip 32 is formed at the top of the trigger 30 which is adapted to engage the bar 29 to stop rotation of the gear 28. The upper end of the trigger 31

is slightly wider than the gear 28 so that when the bar 29 is engaged by the trigger it is sprung outwardly, and upon being released falls back of the trigger.

- 5 6 A spring 33 is secured to the trigger 31 to urge it towards the gear 28. Pivoted to the lower end of the trigger 30 and extending through the wall 5 is a push button 34. When the button 34 is depressed the trigger 10 30 is swung outwardly to release the bar 29 and allows the control gear 28 to rotate a complete revolution and releases a given amount of towel.

15 The towel is threaded in the following manner: The supply is placed in the basket 6 and drawn over the rear edge thereof and between the rollers 11 and 12, thence outwardly through the slot 20 and down to the notch 21; then upwardly and between the 20 rollers 16 and 17 and the end falls into the bottom of the cabinet 1.

Having described my invention, I claim:

1. In a towel cabinet a basket adapted to hold a supply roll of toweling, means for supporting said basket, a door, said door having an aperture formed therein through which the towel projects, and a plurality of rollers within said cabinet through which the towel is threaded, and means comprising

ing an elongated loop hung from one of 30 said rollers and adapted to maintain substantially a vertical position to prevent the towel from winding about said roller.

2. In a device of the class described, a plurality of rollers and means comprising 35 elongated loops hung from one of said rollers adapted to maintain substantially a vertical position to prevent material threaded between said rollers from winding about said roller.

3. A towel cabinet comprising side walls, a door, and a front wall below said door, means for loosely supporting the towel within said cabinet, towel actuating rollers journaled in said side walls, gears secured 40 to one end of said actuating rollers, an idler gear meshing with said gears, a control gear meshing with said idler gear, a trigger pivoted adjacent to said control gear, a bar secured to said control gear, a lip on said 45 trigger to engage said bar, a spring secured to said trigger, a push button pivoted to said trigger and extending through said front wall whereby said trigger may be swung away from said bar to release said 50 control gear for rotation.

In testimony whereof I affix my signature.

JOSEPH N. BORROUGHS.
